CLAIM

The ornamental design for a modular speaker system, as shown and described.

DESCRIPTION

FIG. 1 is a perspective view of the modular speaker system of the present invention.

FIG. 2 is a front view of the modular speaker system of the present invention.

FIG. 3 is an elevation view of the modular speaker system of the present invention.

FIG. 4 is an opposite elevation view of the modular speaker system of the present invention.

FIG. 5 is a rear view of the modular speaker system at the present invention.

FIG. 6 is an exploded perspective view of the modular speaker system of the present invention.

FIG. 7 is a perspective view of the top modular speaker of the modular speaker system of the present invention.

FIG. 8 is a front view of the top modular speaker of the modular speaker system of the present invention.

FIG. 9 is an elevation view of the top modular speaker of the modular speaker system of the present invention.

FIG. 10 is the opposite elevation view of the top modular speaker of the modular speaker system of the present invention.

FIG. 11 is a top view of the top modular speaker of the modular speaker system of the present invention.

FIG. 12 is a bottom view of the top modular speaker of the modular speaker system of the present invention.

FIG. 13 is a rear view of the top modular speaker of the modular speaker system at the present invention.

(Continued)

FIG. 14 is a perspective view of the middle modular speaker of the modular speaker system of the present invention.
 FIG. 15 is a front view of the middle modular speaker of the modular speaker system of the present invention.
 FIG. 16 is an elevation view of the middle modular speaker of the modular speaker system of the present invention.
 FIG. 17 is the opposite elevation view of the middle modular speaker of the modular speaker system of the present invention.
 FIG. 18 is a top view of the middle modular speaker of the modular speaker system of the present invention.
 FIG. 19 is a bottom view of the middle modular speaker of the modular speaker system of the present invention.
 FIG. 20 is a rear view of the middle modular speaker of the modular speaker system at the present invention.
 FIG. 21 is a perspective view of the bottom modular speaker of the modular speaker system of the present invention.
 FIG. 22 is a front view of the bottom modular speaker of the modular speaker system of the present invention.
 FIG. 23 is an elevation view of the bottom modular speaker of the modular speaker system of the present invention.
 FIG. 24 is the opposite elevation view of the bottom modular speaker of the modular speaker system of the present invention.
 FIG. 25 is a top view of the bottom modular speaker of the modular speaker system of the present invention.
 FIG. 26 is a bottom view of the bottom modular speaker of the modular speaker system of the present invention; and, FIG. 27 is a rear view of the bottom modular speaker of the modular speaker system at the present invention.
 The dashed broken lines illustrate portions of the modular speaker system that form no part of the claim.
